CONVERTIBLE SOUND-BOX FOR TALKING-MACHINES.

1,329,906.

Specification of Letters Patent.

Patented Feb. 3, 1920.

Application filed July 7, 1917. Serial No. 179,260.

To all whom it may concern:

Be it known that we, WALTER W. JACKSON and CHRISTIAN PAULSEN, both citizens of the United States, residing, respectively, at 5 Sewaren and at Rahway, in the county of Union and State of New Jersey, have invented certain new and useful Improvements in Convertible Sound-Boxes for Talking-Machines, of which the following is a specification.

Our invention relates to sound reproducing instruments, or talking machines as they are often called, and particularly to improvements in the sound box of such instruments.

Sound records for instruments of the character described are, whether flat or cylindrical, invariably either of the laterally undulating type, as in records of the Berliner class; or of the vertically undulating type, commonly spoken of as the hill and valley type, as perhaps best known in connection with the so-called Edison or Pathé machines.

In the majority of sound reproducing instruments which have thus far been manufactured the sound box is adapted and arranged to play but one of the above described types of record. This is a great inconvenience inasmuch as many beautiful records are found only in one or the other of the two types, but not in both, so that the possessor of the usual machine is entirely shut off from enjoyment of that type of record for which his machine is not adapted.

Some attempts have been made to provide a sound box which could be attached to any usual talking machine and, by a very simple adjustment, be adapted to play either type of record at will. Such sound boxes have, however, not been altogether satisfactory for one reason or another and have, therefore, not secured very wide adoption. In some of such boxes special elbows have been required to be inserted between the sound box and the tone arm to shift the box with reference to the record so as to bring the stylus or needle into such position as to permit either one type of record or the other to be played at will. In other boxes the sound passage through or from the sound box has had to be so located with reference to the diaphragm and other parts of the structure

as to interfere with correct rendering of sound effects.

It is one purpose of our invention, now 55 about to be described, to provide a very simple form of sound box capable of being attached to a very simple form of tone arm and requiring but a slight angular movement about an axis perpendicular to the diaphragm in order to adapt it for reproduction with one type of record or the other. No special elbows or connections between sound box and tone arm are required for changing from one record to the other and 60 in fact elbows are completely eliminated for either form of record while the sound box itself, as well as the tone arm to which it attaches, may be of the simplest possible design and construction. The herein described 70 train of mechanism that transmits the vibration from the stylus to the diaphragm may obviously be used in a sound box adapted to play records of one kind only.

Our invention will be better understood 75 by referring to the accompanying drawings in which Figure 1 represents a side elevation of a talking machine of conventional type having a preferred form of our improved sound box attached and arranged to reproduce records of the vertically undulating type, parts of the machine not necessary to an understanding of the invention being cut away; Fig. 2 represents a central vertical section, twice enlarged, taken through the 80 sound box and end of the tone arm as shown in Fig. 1; Fig. 3 represents a side elevation, on the same scale as Fig. 2, showing the sound box rotated about its central axis through 90°, thus arranged to play records of the laterally undulating type; Fig. 4 is a plan view from the front of the sound box to the same scale as Figs. 2 and 3; and Fig. 5 is a central section, taken on a scale twice that of Figs. 2, 3 and 4, along the line 95 5-5 of Fig. 2.

In the drawings, the tone arm 1 is mounted upon a casing 2 of usual construction and is adapted to rotate horizontally about a vertical axis in a bearing 3. The tone arm is 100 jointed about midway of its length so as to permit its outer section 4 to be raised and lowered about a transverse axis 5. A spring pressed pin 6 and a notch 7 in the coöper

ating parts of the joint maintain the section 4 in raised position when reproduction is not desired.

The outer end 8 of section 4 is bent downwardly in the plane of the tone arm and at an angle of about 60° with the horizontal.

The sound box 9 is of very simple design, comprising a shallow cup recessed to receive the diaphragm 10 and having, centrally extended from the bottom of the cup opposite the diaphragm, a tubular extension 11 which fits over the outer end 8 of tone arm section 4. A pin 12 in end 8 and a corresponding slot 13 in extension 11 permanently unite the sound box with the tone arm while permitting the former to be rotated about its central axis through an angle of 90° .

The diaphragm may be of any usual construction. A lever 14 of thin sheet metal has

its inner end permanently attached to the center of the diaphragm and its outer end attached to the rim of the sound box and arranged to pivot about an axis parallel to the diaphragm and transverse to the lever.

In the particular construction adopted, the plane of lever 14 is perpendicular to the diaphragm while its inner end is twisted so as to bring it flat against the diaphragm to which it is attached by a screw. The

outer end of the lever is also bent into a plane tangent to the rim of the sound box. Screws 15 pass through this bent portion, thus permanently attaching it to the sound box; and by thinning it at 15' the lever is permitted to pivot.

A cross bar 16, permanently fastened at each end to the rim edge of the sound box, carries a pair of knife edges 17. A bell crank lever having one arm 18 constituting a stylus holder lying in the central axis of the sound box and arranged to hold the stylus or needle 19 in the usual way and another arm 20 extending horizontally over the sound box and substantially parallel with lever 14, has two lateral supporting arms 21 provided with notches which seat upon knife edges 17 so as to permit the bell crank lever to rock about said edges. The outer end of arm 20 rests upon but is

separated from arm 14 by a spacing member 22 which is pointed at both ends so as to engage suitable depressions in the two levers. A spring 23 keeps the two levers pressed against the spacing member.

The described construction provides a suitably supported laterally vibratable stylus holder adapted to carry a stylus in front of the central face portion of the diaphragm and connections to transmit the vibrations of the stylus holder to the diaphragm. In the preferred embodiment illustrated the stylus holder and the diaphragm operating lever are supported on independent spaced but parallel pivotal supports and the vibrations of the stylus

holder are transmitted to the diaphragm by positively acting intermediate connections.

The arrangement of lever 14 actuating the diaphragm at the center thereof and pivoted at the rim of the sound box and of the bell crank lever pivoted on the knife edges 17 and fulcrumed on the spacing member 22 constitutes a compound lever whereby any motion of the needle, in the plane of the levers 14 and 20, is transmitted to the center of the diaphragm.

As shown in Figs. 1 and 2, the sound box is so disposed that the needle can only oscillate in the plane which includes the needle, the levers 14 and 20 and the central axis of both sound box and tone arm, and any such oscillation will result in a corresponding oscillation of the diaphragm. Owing to the angle of inclination of the needle a certain component of such movement is necessarily vertical. Records of the vertically undulating type will therefore actuate the needle in correspondence with the undulations and correspondingly oscillate the diaphragm so as to reproduce sound.

If it is desired to reproduce a record of the laterally undulating type, section 4 of the tone arm may be thrown up about the axis 5 and will be held in place by pin 6 and notch 7. The former vertically undulatory record may now be changed for a laterally undulating record and the sound box is rotated about its axis until the other end of slot 13 engages pin 12. This rotation will amount to 90° and the plane of vibration of the needle or stylus will, after the needle has again been lowered upon the record, now be perpendicular to the axial plane of the tone arm and sound box. The needle will, of course, be inclined to the record at the same angle as in the former case since the sound box has merely been rotated about the needle as an axis. The needle will now move in correspondence with the lateral undulations thereby appropriately actuating the diaphragm so as to reproduce the sounds represented by the record.

It will be noticed that, whether the sound box be arranged for records of the vertically undulatory type or for records of the laterally undulatory type, the distance from the needle point to the axis of rotation of the tone arm is fixed and invariable. And if, as should preferably be the case, this distance be the same as the distance between the axes of rotation of the record and of the tone arm, then the path of the needle across the record will always be accurately at right angles to the individual grooves of the record. There will be, consequently, no tendency for the needle to jump from its groove while a record is being reproduced.

It will also be observed that the sound waves are led from the sound box along a

path normal to the center of the diaphragm and that this path is fairly direct to the amplifying horn (not shown) as well as free from tortuous elbows and so called goose necks. This path is, furthermore, accurately the same for either type of record.

Instead of locating the needle in the axis of the sound box we may, within the spirit of the invention locate it parallel with said axis but at some or, substantially, any other point upon the lever 20. The distance between needle point and axis of rotation of the tone arm will no longer be the same for the two positions of the sound box and hence there will be some tendency, in one or both of these positions, for the needle to leave its groove.

Furthermore, while we prefer the particular arrangement of compound lever, connecting needle and diaphragm, shown in the drawings herewith, other forms and arrangements of lever may be substituted therefor within the spirit of the invention and within the scope of the claims which follow.

We claim—

1. In a talking machine, a sound conductor having one end disposed to move across and parallel with a sound record and a sound box attached to said end, the central axes of the sound conductor at said end and of the sound box being coincident, said sound box being provided with a needle also coincident with said axes of sound conductor and sound box and arranged to oscillate in a single plane normal to the diaphragm, and means operatively connecting the needle and the diaphragm, said sound box being arranged to be rotated axially upon the sound conductor through a quarter turn.

2. In a talking machine, a tone arm having one end pivoted upon a vertical axis and its outer end bent downwardly, a sound box axially coincident with said outer end and axially rotatable thereon, a needle normal to the center of the sound box, and a motion transmitting lever connected between said needle and the diaphragm the plane of oscillation of the needle being normal to the diaphragm and the same as that of the lever.

3. A convertible sound box for talking machines comprising a recessed cup one side of which is closed by a diaphragm while the other side has an axial extension adapted to be connected with a sound conductor, means arranged to rock upon a fixed axis parallel to the diaphragm for holding a needle in the axis of the sound

box, and a lever operatively connected between the diaphragm and the said rocking means.

4. In a talking machine, a sound conductor having its inner end pivotally mounted so that its outer end may move across and parallel with a sound record and a sound box attached to said outer end, said sound box being axially coincident with said outer end, and axially rotatable thereon, a diaphragm, a needle normal to the center of said diaphragm, and a motion transmitting lever connection between said needle and the diaphragm, the plane of oscillation of the needle being normal to the diaphragm.

5. In a sound box, in combination with a diaphragm, a laterally vibratable stylus holder operatively supported in front of the central face portion of the diaphragm and lever connections to convert the lateral vibrations of the stylus holder into vibrations of the diaphragm in a direction normal thereto, substantially as described.

6. A sound box comprising a diaphragm, a laterally vibratable stylus holder operatively supported in front of the central face portion of the diaphragm, lever connections for transmitting the vibrations of the stylus holder to the diaphragm, and means for supporting said sound box rotatably about its own axis so that in one position of rotation it will play a lateral record and in another position of rotation it will play a hill-and-dale record.

7. A sound box comprising a diaphragm, a lever, pivotally supported, and attached to the center of the diaphragm, a laterally vibratable stylus holder supported in front of the central face portion of the diaphragm and substantially coaxial therewith, and connections to transmit vibrations of the stylus holder to said lever.

8. In a sound box in combination with a diaphragm, a pair of levers mounted on parallel pivots for movement in a plane normal to the diaphragm and operatively connected to constitute a compound lever, one end of one lever being connected to the center of the diaphragm and one end of the other lever being formed to provide a stylus holder positioned to hold a stylus in the axis of the sound box for lateral movement about an axis transverse to but passing through the axis of the sound box.

In testimony whereof we have hereunto set our hands.

WALTER W. JACKSON,
CHRISTIAN PAULSEN.
